PROPELLER

James E. Carol, Los Angeles, Calif., assignor, by direct and mesne assignments, of forty-six and two-thirds per cent to C. Bland Jamison, thirty-three and one-third per cent to Collins Mason, and twenty per cent to Arthur E. Wright, all of Beverly Hills, Calif.

Application May 27, 1941, Serial No. 395,398

3 Claims. (CL 170—173)

My invention is in the art of propellers and, more particularly, it has to do with ferrules and reinforcements for rendering wooden blades safely useable in variable pitch propellers as well as in other propeller hubs in which the blades are detachably mounted in the hub.

The difficulties attending such uses of wooden propeller blades are well known and have long existed. In conventional practice, the reduced and rounded shank end of the blade is encased in a ferrule which is rotatably mounted in a radially disposed socket in the hub member, the blade tapering outwardly from the rounded reduced shank to an adjacent relatively larger cross-section, usually oval. It has been the practice to terminate the ferrule substantially flush with the periphery of the socket, or at the outer end of the rounded shank portion of the blade, which is the weakest section of the blade. Thus the fulcrum point, as between the ferrule and blade, is at the outer end of the reduced shank section where the trailing edge of the blade abuts the peripheral edge of the ferrule, so that the greatest breaking moment is at this weakest section of the blade. The result of this construction has been that wooden blades often break at that point.

One of the principal objects of my invention is to provide a ferrule which overcomes this shortcoming of known devices, and one which is so designed and mounted that it effectively reinforces the weakest section of the blade and provides the fulcrum point at that portion of the blade most capable of withstanding stresses resulting from use of the blades as airfoils. Other objects and advantages are inherent in my invention and they will appear hereinafter.

The broader aspects of my invention are defined by the appended claims, but, for the purpose of making my invention understood, I shall now describe specific adaptations thereof, making reference to the accompanying drawings, in which:

Fig. 1 is a longitudinal section of a propeller hub and blade assembly embodying my invention;

Fig. 2 is a section on line 2—2 of Fig. 1;

Fig. 3 is a section similar to Fig. 2, but showing my invention applied to a blade of oval cross-section; and

Fig. 4 is an elevation of the shank portion of a propeller showing a variational form of my invention.

In the drawings, I show at 5 a propeller blade having a round, reduced shank end 6, from which

the blade tapers outwardly into an adjacent portion 7 of larger and stronger cross-section—the leading and trailing edges of the blade being designated by the numerals 8 and 9, respectively. Of course the cross-sectional shape of blade portion 7 may be oval, in fact conventional blades are so shaped, but I find that it facilitates manufacture and application of the ferrule if portion 7 tapers toward shank 6 in round cross-section, as then it is possible to manufacture the blades and ferrules with uniform, true and conforming tapers and it is relatively easy to mount the ferrules onto the propeller.

The numeral 10 designates a fragmentary section of a hub assembly presenting a radial thimble or barrel 11 having a bore 12 to receive the shank 6 of the blade. The motor drive shaft M is splined to the hub portion 11a. Conventionally, such thimbles are longitudinally split and clamped together by bolts 14 and ring 14a so that the bolts may be loosened and ring 14a loosened to permit rotation of the blade about its longitudinal axis to adjust the pitch. One end of ring 14a terminates in a bolt portion which extends through an opening in a flange presented by the other end of the ring, as shown in dash lines in Fig. 1. A nut, not shown, screws onto the bolt portion. Before applying the ferrule, to be later described, I turn or otherwise cut a shallow V-shaped recess 15 circumferentially of shank 6 and fit into the recess a split sleeve 16 having a V-shaped undersurface 17 to conform to recess 15 and a plane outersurface. This enables the shank section 21 of the ferrule, to be hereinafter described, to be of uniform cross-section and eliminates the necessity of spinning the ferrule onto the blade shank to cause the ferrule itself to conform circumferentially to the recess 15, as is customary.

My improved ferrule is generally designated by the numeral 20 and comprises an inner end portion 21 of round cross-section to snugly fit and enclose the shank 6 of the blade, and an extension portion 22 which snugly fits and encloses the blade portion 7, the ferrule flaring outwardly from the portion 21 to a larger cross-section conforming to the taper of the blade. The outer peripheral edge is interiorly beveled at 23 to overly the reversely beveled shoulder 24 of blade portion 7.

Screws 25 extend through ferrule portion 21 into and through split sleeve 16 and into the propeller. Thus sleeve 16 reinforces the shank and prevents longitudinal movement of the blade with respect to the ferrule.

By this construction, the fulcrum **F** is at the trailing edge of that portion of the blade which has greatest strength while the reduced and substantially weaker shank section is fully reinforced throughout.

Transverse rivets **27** through the portion **22** of the ferrule and portion **7** of the blade further secure the blade against longitudinal escape from the ferrule and resist splintering at that point.

While various conventional means are known for preventing longitudinal escape of the ferrule from the thimble, I show for the purpose annular flanges **30** on the blade shank and annular recesses **31** in the thimble and projecting at their inner ends into the channel.

In Fig. 3, the blade section **7a** and ferrule section **22a** are shown as oval in cross-section and have the rivets **27a** thereacross. Otherwise the device is identical with Figs. 1 and 2.

In Fig. 4, the ferrule portion **22b** is oval in cross-section to conform to a blade portion **1b** of like cross-section, and has its outer peripheral edge **35** extending diagonally along the width of the propeller blade portion **1b**, the ferrule being relatively longer at the trailing edge than at the leading edge. This not only eliminates weight while maintaining the fulcrum at the ideal point, but also lends flexibility to the blade.

I claim:

1. In combination, a propeller hub having a radial socket, a blade having a shank extending into the socket, and a ferrule encompassing the shank, said ferrule with its carried shank being

secured against escape from the socket and having a portion projecting outwardly from the hub and encompassing the blade adjacent the shank, the peripheral edge of the projecting ferrule portion being disposed diagonally inwardly from a point on the trailing edge of the blade spaced outwardly from the hub to a point on the leading edge of the blade nearer the hub.

2. A propeller of the class described including, 10 in combination, a blade having a shank portion oppositely tapered towards a point intermediate its ends, said tapers intersecting medially of the shank whereby to provide a reduced diameter medial portion, a longitudinally split sleeve embracing the tapered shank portion, said sleeve having an inner surface tapered to conform to the tapered shank portion, and means for constricting the sleeve about the tapered shank portion.

20 3. A propeller of the class described including, in combination, a blade having a shank oppositely tapered towards a point intermediate its ends, said tapers intersecting medially of the shank whereby to provide a reduced diameter medial portion, a longitudinally split sleeve embracing the tapered shank portion, said sleeve having an inner surface tapered to conform to the tapered shank portion, a ferrule constricting the sleeve about the tapered shank portion and means securing the sleeve and ferrule against relative longitudinal movement.

JAMES E. CAROL.
